UNITED STATES PATENT OFFICE.

WALTER G. CONGER, OF INDEPENDENCE, MISSOURI

RADIOTELEPHONE RECEIVER BLOCK.

Application filed June 23, 1923. Serial No. 647,386.

To all whom it may concern:

Be it known that I, WALTER G. CONGER, a citizen of the United States, residing at Independence, in the county of Jackson and State of Missouri, have invented certain new and useful Improvements in Radiotelephone Receiver Blocks, of which the following is a specification.

This invention relates to a radio telephone receiver block, designed primarily for use in connection with radio receiving apparatuses, and the invention has for its object to provide, in a manner as hereinafter referred to, a receiving block of such class, with means whereby a plurality of telephone receivers can be connected with a radio receiving apparatus for use simultaneously by a plurality of persons and furthermore, to provide the block with means, in a manner as hereinafter referred to, for successively cutting in or placing in circuit with the radio receiving apparatus, telephone receivers without cutting out the telephone receiver or receivers positioned in circuit in advance of the cutting in or closing the circuit for the subsequently connected receivers, or in other words, providing means where one or more telephone receivers can be connected in circuit with a radio receiving apparatus without inconvenience when a change in the number of telephone receivers for use is desired.

Further objects of the invention are to provide, in a manner as hereinafter set forth, a radio telephone receiving block, which is simple in its construction and arrangement, strong, durable, compact, thoroughly efficient in its use, conveniently operated, readily set up and comparatively inexpensive to manufacture.

With the foregoing and other objects in view, the invention consists of the novel construction, combination and arrangement of parts as hereinafter more specifically described and illustrated in the accompanying drawings, wherein is shown an embodiment of the invention, but it is to be understood that changes, variations and modifications can be resorted to which come within the scope of the claim hereunto appended.

In the drawings wherein like reference characters denote corresponding parts throughout the several views:—

Figure 1 is a top plan view of a radio telephone receiver block, in accordance with this invention.

Figure 2 is an inverted plan view of a radio telephone receiver block, in accordance with this invention.

Figure 3 is a section on line 3—3, Figure 1.

Figure 4 is a section on line 4—4, Figure 1.

Figure 5 is a section on line 5—5, Figure 1.

Figure 6 is a top plan and Figure 7 is an inverted plan of a modified form.

Figures 8 and 9 are top plan views of modified forms of clip contacts.

In either form of radio receiver block as shown, in accordance with this invention, it includes a base formed of any suitable insulation material and such base may be of any desirable contour, but as shown is squared and provided with rounded corners.

Referring to Figures 1 to 5 of the drawings, 10 indicates the base, having its lower face formed with a circular recess or pocket 11 of substantial depth and extending through the base 10, near each corner thereof is a hold-fast device 12, for fixedly securing the base 10 to a suitable support. Arranged against the lower face of the base 10 is a plate 13 of any suitable material, which is employed for closing the recess or pocket 11 and which is secured in position by the hold-fast devices 12.

Connected to and projecting upwardly from the base 10, is a pair of primary terminals, as indicated at 14, 15 and each of which is in the form of a binding post comprising a body portion 16, formed with a transverse opening 17, a vertically disposed opening 18 which communicated with the opening 17 and has a threaded wall for engagement by the threaded shank 19, of a binding screw 20. The body portion 16 is formed with a socket 21 having a threaded wall which is engaged by the threaded shank 22 of a binding screw 23 carrying a pair of disks 24, 25.

The binding screws 20 of the terminals 14, 15, are employed for detachably connecting respectively to the terminals 14, 15, circuit conductors 26, 27, which lead to a radio receiving set, not shown.

The radio telephone receiver block, is shown, by way of example, for use in connection with six telephone receivers but this number can be increased or diminished if desired, and the drawing illustrates two receivers connected with the base 10. The

receivers are indicated at 28, 29 and each includes a pair of circuit wire connections 30, 31 formed at the free end with a circuit closing tip 32.

5 Associated with the telephone receivers, is a series of secondary terminals, two of which are indicated at 33 and the others at 34. The secondary terminals 33 are constructed in the same manner as the terminals 14 or 15 and are clearly shown in Figure 5. Each of the secondary terminals 34 is in the form of a binding post and comprises a body portion 35 provided with a pair of transversely extending superposed openings 36, 37. The body portion 35 is furthermore provided with an opening 38 disposed at right angles with respect to and communicating with the opening 37. The wall of the opening 38 is threaded and with 10 which engages the threaded stem 39 of a binding screw 40. The body portion 35 at its upper end is formed with a vertically disposed opening 41 which communicates with the opening 36 and has a threaded wall, 15 and engaging with the said wall is the threaded stem 42 of a binding screw 43. The body portion 35 is furthermore provided at its lower end with a socket 44, having the wall thereof threaded and engaging 20 with said wall is a threaded stem 45 of a binding screw 46. Carried by the binding screw 46 is a pair of disks 47, 48.

Each of the secondary terminals 34, as stated, is provided with the pair of binding screws 40, 43 and which are employed for connecting a pair of contact tips 32 of a pair of telephone receivers with a terminal 34, as shown in Figures 1 and 4. The terminals 33 of the secondary terminal are 25 employed for connecting but one telephone receiver tip 32 therewith, and the binding screw for such purpose is indicated at 49 and the other binding screw of each terminal 33 is indicated at 50.

30 The binding screws 46 of the terminals 34 are not only employed for securing circuit connections with said terminals, but are further employed for fixedly securing the terminals 34 to the base 10, and for such purpose the screws 46 extend up through openings 51 formed in the base and engage in the body portions 35. The binding screw 50 of each terminal 33 of the secondary terminals is employed for the 35 same purpose as the binding screw 46 and extends up through an opening 51.

The base 10 has secured therewith a series 40 of contacts 52 and the said contacts associate with the terminals 34 and one of the terminals 33. Each of the contacts 52 includes a head formed with a shank 53 which extends through the opening 54 formed in the base 10 and has a threaded lower portion 55 carrying a pair of securing nuts 56. The contacts 52 are spaced

from the terminals 34 and that terminal 33 of the secondary terminals, and extending from the shank 53 of each contact to a binding screw 46 of each terminal 34 and to the binding screw 50 of the terminal 33 is 50 a circuit connection 57. The other terminal 33 of the secondary terminals is connected to the terminal 14 by a circuit connection 58.

Rotatably mounted in the base 10, centrally thereof, is a vertically disposed shaft 59, provided at its upper end with a cap member 60 of insulation. The shaft 59 extends into the recess 11 and has connected therewith by the securing device 61, a circuit connection 62, which is connected to 75 the lower end of the terminal 15. Secured to the shaft 59 so that it will be carried therewith, when the shaft 59 is shifted, is a circuit opening and closing member 63, having a depending outer end 64, for engagement with the contacts 52.

The member 63 is employed for selectively engaging with the contacts 52 for the purpose of closing the circuit to the receivers.

In Figure 1 of the drawings the contacts are indicated at A, B, C, D, E and F, for the purpose of clearly setting forth the closing of the circuits with respect to the telephone receivers. It will be assumed that the member 63 has been shifted to engagement with the contact A which would close the circuit to the receiver 29, through conductor 27, circuit connection 62, shaft 59, member 63, contact A, circuit connection 57, the secondary terminal connected with the contact A, receiver 29, secondary terminal arranged opposite the terminal 14, circuit connection 58 and conductor 26. Now it will be assumed that member 63 has been shifted to contact D. The circuit would be closed through the receivers which are connected to the secondary terminals in circuit with the contacts D, C, B, A, terminal 33, and circuit connection 58 leading from the terminal 33 to the terminal 44. If the member 63 is shifted to engage contact F, then all the receivers would be in circuit. The receivers are employed for bridging the circuit between the secondary terminals.

Referring to Figures 6 and 7 of the drawings, the base is indicated at 65 and the recess or pocket in its lower face at 66. Connected to the base 65 is a pair of primary terminals 67, 68, to which are secured respectively the conductors 69, 70, which are in circuit with the radio receiving set. Secured to the base 65 is a series of secondary terminals 71, 72, 73, 74, 75, 76, 77, 78, 79, 80, 81 and 82. Secured to the base 65 is a series of contacts 83, 84, 85, 86, 87 and 88. Rotatably connected to the base, centrally thereof, is a shaft 89 provided with a circuit opening and closing member 90.

Each of the terminals 67, 68 and 71 to 82, inclusive, is constructed in the same manner as a secondary terminal 33 hereinbefore referred to. Each of the contacts 83 to 88 is constructed in the same manner as the contacts 52 hereinbefore referred to. The shaft 89 and circuit opening and closing member is set up and constructed in the same manner as the shaft 69 and the member 63 hereinbefore referred to. Leading from the terminal 68 to shaft 89 is a circuit connection 91. Leading from the terminal 67 to the terminal 71 is a circuit connection 92. Leading from the contact 83 to the terminals 72 and 73 are circuit connections 93. Leading from the contact 84 to the terminals 74 and 75 are circuit connections 94. Leading from the contact 85 to the terminals 76 and 77 are the circuit connections 95. Leading from the contact 86 to the terminals 78 and 79 are circuit connections 96. Leading from the contact 87 to the terminals 80 and 81 are the circuit connections 97. Leading from the contact 88 to the terminal 82 is the circuit connection 98.

In the form shown in Figure 7 a pair of secondary terminals is employed for connecting a telephone receiver 99 or 100 with the base.

If the member 90 is shifted to engage the contact 83, the circuit to the receiver 99 will be closed, as is obvious, and if shifted to engage the other contacts, additional receiver circuits will be closed as is obvious.

In lieu of setting up the secondary terminals in the manner as shown in connection with either one of the forms, clamping clips of the single type as shown in Figure 8 and indicated at 101 can be employed in the form shown in Figures 6 and 7 and clamping clips of the duplex type, as indicated at 102, in Figure 9 can be shown in connection with the form shown in Figures 1 and 2. The clips illustrated in Figures 8

and 9 are of known construction and it is thought unnecessary to describe the same.

From the foregoing construction of radio telephone receiver block a device is set up whereby telephone receivers can be successively cut in with a radio receiving set, or a series of telephone receivers cut in without cutting out a receiver or receivers already cut in, and which operation is had without any inconvenience whatsoever, and although the preferred embodiment of a radio telephone receiver block in accordance with this invention is as described and illustrated, yet it is to be understood that changes in the details of construction can be had which fall within the light of the invention as claimed.

What I claim is:

A radio telephone receiver block comprising a base, a series of spaced terminals mounted thereon and each provided with means adapted to detachably connect therewith one of the plugs of the two plugs of each of a pair of telephone receivers, a series of spaced contacts mounted on said base, a circuit conductor secured with and extending from each of said contacts to each of said terminals, means for securing said conductors to said terminals and further for securing the terminals to the base, circuit forming connections secured to said pair of terminals and adapted to lead to a radio receiving set, a circuit conductor leading from one of the terminals of said pair to one of the terminals of said series, a shiftable circuit opening and closing member supported upon the base and adapted to selectively engage with said contacts to close a circuit for the connected receivers, and a circuit conductor leading from the other of said pairs of terminals to said member.

In testimony whereof, I affix my signature hereto.

WALTER G. CONGER.
